(57) **CLAIM**

The ornamental design for a camping trailer, as shown and described.

DESCRIPTION

FIG. 1 is a front perspective view of the camp trailer showing the new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top view thereof;

FIG. 7 is a bottom view thereof; and,

FIG. 8 is a rear perspective view thereof.

The broken lines in the accompanying drawings refer to environmental structures and form no part of the claimed design.
